UNITED STATES PATENT OFFICE.

FRANK X. MAIER, OF STERLING, ILLINOIS.

SPRING HINGE.

1,417,084.

Specification of Letters Patent. Patented May 23, 1922.

Application filed November 1, 1921. Serial No. 512,029.

To all whom it may concern:

Be it known that I, FRANK X. MAIER, a citizen of the United States, residing at 408 9th St., Sterling, in the county of Whiteside, 5 State of Illinois, have invented a new and useful Spring Hinge; and I do hereby declare the following to be a full, clear, and exact description of the invention, such as will enable others skilled in the art to which 10 it appertains to make and use the same.

The invention relates to spring hinges of the type used in connection with screen doors, and has for its object to provide a hinge of this character having a double 15 spring, thereby providing means whereby upon breakage of one of the springs the hinge will not be rendered worthless and inoperative. Also to provide one of the leaves of the hinge with apertures, which 20 apertures receive L-shaped lugs carried by a plate secured to the door frame, said lugs and apertures forming means whereby the hinge may be easily and quickly removed 25 from the door frame without the use of a screw driver.

A further object is to provide the door carried leaf with a lug, which lug when the door is partially opened is engaged by a pivoted finger thereby holding leaves of the 30 hinge at angles to each other and allowing the hinge to be quickly detached from the lugs carried by the plate secured to the door frame. Also to provide a finger engaging member on the door frame carried leaf 35 whereby said leaf may be easily raised against the action of the springs.

With the above and other objects in view the invention resides in the combination and arrangement of parts as hereinafter set 40 forth, shown in the drawings, described and claimed, it being understood that changes in the precise embodiment of the invention may be made within the scope of what is claimed without departing from the spirit 45 of the invention.

In the drawings:

Figure 1 is a front elevation of the hinge showing the same applied to a portion of a screen door and a portion of a door frame.

50 Figure 2 is a horizontal sectional view taken on line 2—2 of Figure 1.

Figure 3 is a horizontal sectional view taken on line 3—3 of Figure 1.

55 Figure 4 is a perspective view of a portion of a door frame, showing the lug carrying plate attached thereto.

Figure 5 is a perspective view of the pivoted leaf holding member.

Referring to the drawings, the numeral 1 designates a portion of a door frame, and 6e 2 a portion of a screen door. It is the present practice to remove screen doors from the door opening during the winter and store the same until the following summer. When this is done, it is necessary to detach the 65 screen hinge from the door frame 1 to which it is attached by screws, hence a great deal of work is involved and at the same time when doors are again hung the holes are stripped or enlarged incident to constant 70 use. The hinge 3 comprises a leaf 4 having outstanding flanges 5, to which flanges are pivotally connected by means of a hinge pin 6, the flanges 7 of a hinge leaf 8. Leaf 8 is detachably connected to a plate 9 which 75 is secured to a door frame 1 by means of L-shaped lugs 10, which lugs overlie the inner edge 11 of the leaf 8, and is held against displacement on the plate 9 by the flange 12 carried by the outer edge of the 80 plate 9, which engages the outer edge of the leaf 8. It will be noted by referring to Figure 2 that when the screen door 2 is moved in the direction of the arrow *a* that coiled springs 13, which are carried by the 85 pins 6 and have their opposite extending ends 14 in engagement with the outer faces 90 of the leaves 8 and 4, the leaf 8 will be maintained in engagement with the plate 9 at all times during a door opening and closing 95 operation. However when it is desired to detach the leaf 8 from the plate 9, this may be accomplished by pulling outwardly on the finger engaging member 15 carried by 100 the leaf 8 and removing said leaf 8 from its interengagement with the hooked lugs 10 carried by the plate 9. However if it is desired to hold the leaf 4 at an outward obtuse angle to the plate 8, this may be accomplished by manually opening the door 105 to the desired position, and then moving the pivoted member 16 until its end 17 is placed in engagement with the flange 18 carried by the inner edge of the leaf 4 thereby preventing the leaf 4 from moving inwardly against 110 the action of the coiled springs 13. When the leaves are held at an angle to each other as described above, it will be seen that upon an inward movement of the door 2 the outer end of the leaf will move outwardly from engagement with the plate 9 to a position where the hinge may be easily and quickly

5 moved out of engagement with the hooked lugs 10, thereby allowing the door to be easily and quickly removed from the door frame for storage purposes. The plate 9 remains attached to the door frame 1 at all times, and consequently when the door is again hung is properly positioned for use. The plate 9 is secured to the door frame by means of screws 19 and the plate 8 is preferably provided with apertures 20, which register with the screws 19, thereby allowing the screws 19 to be tightened or adjusted without removing the door from the door opening.

10 15 From the above it will be seen that a screen door hinge is provided which is simple in construction and one which may be easily and quickly attached to a door frame.

20 The invention having been set forth what is claimed as new and useful is:—

1. A hinge comprising pivotally connected leaves, the adjacent edges of the leaves being spaced from each other, a supporting plate, hooked lugs carried by said plate and 25 adapted to hook over the inner edge of one of the leaves, a flange carried by the supporting plate and engaging the outer end of said

last named leaf, a lug extending outwardly at an angle from one of the leaves, a member pivoted to the leaf without the lug, said member being of sufficient length to hold the leaves at angles to each other when its end is in engagement with the lug, the pivotal point of the leaves being outwardly disposed in relation to the adjacent edges 35 of the leaves and springs for normally forcing said leaves in the direction of alignment with each other.

2. A spring hinge comprising hingedly connected leaves, springs for normally forcing said leaves towards an aligned position, a lug carried by one of said leaves, a member pivoted to the other leaf and adapted to be moved into engagement with the lug of the adjacent leaf for holding the leaves in 45 angular positions in relation to each other.

In testimony whereof I have signed my name to this specification in the presence of two subscribing witnesses.

FRANK X. MAIER.
